UNITED STATES PATENT OFFICE

151,853

DESIGN FOR A HAMMER HEAD

William L. Ludwick, Mount Carmel, Conn., assignor to The Peck, Stow & Wilcox Company, Southington, Conn., a corporation of Connecticut

Application March 1, 1946, Serial No. 126,990

Term of patent 14 years

(Cl. D93—4)

To all whom it may concern:

Be it known that I, William L. Ludwick, a citizen of the United States, residing at Mount Carmel, in the county of New Haven and State of Connecticut, have invented a new, original, and ornamental Design for a Hammer Head, of which the following is a specification, reference being had to the accompanying drawing, forming part thereof, in which—

Fig. 1 is a front view in elevation of a hammer head, showing my new design;

Fig. 2 is a side view in elevation of the hammer head shown in Fig. 1; and

Fig. 3 is a sectional view taken substantially in the plane of the line 3—3 of Fig. 1.

The essential features of my design reside in

the hammer head of the configuration shown and particularly in the flat area at the front of the neck and in the rearwardly displaced poll.

I claim:

The ornamental design for a hammer head, substantially as shown and described.

WILLIAM L. LUDWICK.
